UNITED STATES PATENT OFFICE.

JOHN TALLY OVERSTREET, OF UVALDE, TEXAS.

SEALING MEANS FOR RECEPTACLES.

Application filed September 21, 1921, Serial No. 502,231. Renewed November 19, 1923.

To all whom it may concern:

Be it known that I, JOHN T. OVERSTREET, a citizen of the United States, residing at Uvalde, in the county of Uvalde and State 5 of Texas, have invented certain new and useful Improvements in Sealing Means for Receptacles, of which the following is a specification.

This invention relates to receptacles and 10 more particularly to the sealing means therefor.

An important object is to provide a receptacle having a cover provided with attaching prongs adapted to be received within 15 an annular channel shaped member and bent thereby whereby the cover is securely held in position without the necessity of employing solder or the like.

Further, the invention aims to provide a 20 cover having novel means whereby the unauthorized opening of the same during shipment or handling in trade may be detected.

A further object is to provide a receptacle which is of highly simplified construction, desirable in use and cheap to manufacture.

Other objects and advantages of the invention will be apparent during the course of the following description.

30 In the accompanying drawing forming a part of this application and in which like numerals are employed to designate like parts throughout the same,

Figure 1 is a detail sectional view through 35 the receptacle provided with the improved cover.

Figure 2 is a plan view of the receptacle with the cover removed.

Figure 3 is a perspective of the cover, 40 the view illustrating the means for securing the cover to the receptacle.

Figure 4 is a fragmentary sectional view of the receptacle illustrating the construction of the annulus secured within the upper 45 portion of the same.

In the drawing wherein for the purpose of illustration is shown a preferred embodiment of the invention, the numeral 5 designates the receptacle which is of cylindrical 50 formation and is adapted for the reception of condensed milk or other liquids, or, if desired, solids.

As illustrated in Figure 1, an annulus 55 generally designated by the numeral 6 is set within the upper portion of the recepta-

cle and has one edge portion bent upon itself to provide a flange 7 engaged with the outer side of the receptacle and secured thereto by means of solder or the like. It will be noted that the flange 7 which is annular co-operates with the adjacent side of the annulus 6 in forming an annular groove which snugly receives the upper end of the receptacle 5.

The annulus 6 which is thus securely held within the receptacle is U-shaped in cross section and is therefore provided with an annular channel opening out through the upper end of the receptacle whereby the attaching prongs 8 carried by the cover 9 may be inserted into the channel. The attaching or sealing prongs 8 have their terminal portions curved outwardly as indicated at 10 so that when the same contact with the bottom of the channel in the annulus the 15 prongs will be coiled in the manner illustrated in Figure 1. With the sealing prongs 8 thus securely held in position the cover 9 is firmly attached to the receptacle and when once removed cannot be again 20 applied to the receptacle in a manner to prevent subsequent detection.

The cover 9 is provided with an upstanding side wall 12 which snugly contacts with the inner side of the annulus 6 to provide 25 a liquid tight connection between the annulus and the cover. The side wall 12 is formed by offsetting the cover adjacent its edge and by thus offsetting the cover a flange 14 is provided. In assembling the 30 receptacle subsequent to filling a gasket 15 is arranged between the flange 14 and the bead 18 formed at the upper edge of the inner side of the annulus 6. When forcing the prongs into position the gasket 15 is 35 tightly pressed between the bead 18 and the flange 14 to provide a means for preventing leakage and to form an air-tight closure.

The gasket 15 is held against outward spreading by means of the inwardly bent 40 edge portion or bead 20 of the flange 14. It is thus seen that the bead with which the prongs 8 are formed integral acts as a means for preventing spreading of the gasket. Further, it will be noted that the bead 20 45 contacts with the outer side wall of the annulus 6 and prevents the entrance of dirt, etc., into the channel of the annulus. However, the bead 20 terminates inwardly of the attaching flange 7 to permit a small tool to be 50

forced between the bead 20 and the outer side wall of the annulus for the purpose of removing the cover.

In use, the cover may be removed as above stated and when once removed the prongs 8 may be cut off if desired so that the cover may be reapplied to protect the contents of the receptacle.

The improved receptacle is cheap to manufacture, and may be economically seated since it is not necessary to employ solder as is customary in receptacles of this type.

Having thus described the invention, what is claimed is:—

15 1. A receptacle comprising a body, an annulus secured to the end of the receptacle and having a trough, and a cover provided with sealing prongs received in said trough, the terminal portions of said prongs being 20 curved whereby the prongs are coiled upon insertion into said trough.

2. A receptacle comprising a cylindrical body, an annulus secured within the upper portion of the cylindrical body and being of 25 U-shaped formation, said annulus being provided with a channel, a cover having an offset defining a side wall and a flange, said flange being provided with a bead, sealing prongs, carried by said bead and having 30 their terminal portions curved longitudinally whereby the prongs are coiled upon insertion into said channel, and a gasket confined between said flange and the inner side wall of said annulus and held in position by said 35 bead.

3. A receptacle comprising a cylindrical body, an annulus secured within the upper

portion of the cylindrical body and being of U-shaped formation said annulus being provided with a channel, a cover having an offset defining a side wall and a flange, said flange being provided with a bead, and sealing prongs carried by said bead and having their terminal portions curved longitudinally whereby the prongs are coiled upon insertion into said channel, said bead being engaged with the outer side wall of said annulus to close said channel, said side wall being snugly engaged with the inner side wall of said channel.

4. A receptacle comprising a body, an annulus secured within said body and having spaced side walls defining a channel, a cover having an offset defining a side wall and a flange, the edge portion of said flange being bent inwardly to form a bead, spaced sealing prongs carried by said bead and adapted for insertion into said channel, said bead being engaged with the outer side wall of said annulus to close said channel, 60 the inner side wall of said annulus being provided with a bead extending into said channel and confining said prongs within the channel, and a gasket confined between said flange and said second named bead and held, against outward movement by said first named bead.

In testimony whereof, I have affixed my signature in the presence of two witnesses.

JOHN TALLY OVERSTREET.
